[57] CLAIM

The ornamental design for a combined covered pail and detachable rim, as shown and described.

DESCRIPTION

FIG. 1 is a front perspective view of a combined covered pail and detachable rim showing my new design; FIG. 2 is a perspective view of the top of the lid; FIG. 3 is a perspective view of the bottom of the lid; FIG. 4 is a perspective view of the top of the rim; FIG. 5 is a perspective view of the bottom of the rim; FIG. 6 is a front perspective view of the pail, similar to FIG. 1, with the lid removed; FIG. 7 is a bottom plan view of the pail; and FIG. 8 is an exploded rear elevational view of FIG. 1.

FIG. 1.

FIG. 2.

FIG. 3.

FIG. 4.

FIG. 5.

FIG. 6.

FIG. 7.

FIG. 8.
